AUGUST SUNDH, OF YONKERS, NEW YORK, ASSIGNOR TO OTIS ELEVATOR COMPANY, OF JERSEY CITY, NEW JERSEY, A CORPORATION OF NEW JERSEY.

COMPOUND BRAKE.

No. 849,283.

Specification of Letters Patent.

Patented April 2, 1907.

Application filed June 19, 1905. Serial No. 265,995.

To all whom it may concern:

Be it known that I, AUGUST SUNDH, a citizen of the United States, residing at Yonkers, in the county of Westchester and State 5 of New York, have invented a new and useful Improvement in Compound Brakes, of which the following is a specification.

My invention relates to brakes, and has for its object the provision of means for applying primary braking members and utilizing the moving force of the driving means for applying secondary braking members adjacent the primary members, thereby producing a powerful compound brake, which requires a 15 comparatively small power to set the brakes.

A further object of my invention is to provide primary and secondary braking members for the rim of a single friction-pulley and limiting substantially all the strain thereon 20 to a circumferential tension.

Another object is to provide a compound and double brake with the parts arranged symmetrically and so that the rotary force of the driving-shaft may be used in either 25 direction of rotation to apply the secondary braking members from the primary braking members and adjacent each other.

Other objects of the invention will appear hereinafter, the novel combinations of elements being set forth in the claims.

The invention is of the type employing one or more springs for applying the brake, the same being released by electromagnetic means and is similar in its action to that disclosed 35 in the patent to Sundh and Lindquist, 772,005, October 11, 1904, hoisting apparatus; in the patent to Sundh, 757,789, April 19, 1904, elevator-brake mechanism, and in my copending application, Serial No. 240,613, 40 filed January 11, 1905, elevator-brakes. In the two patents and the application mentioned, however, the secondary braking members are not adjacent the primary members, but are applied to a hoisting drum or 45 drums, whereas in the present construction both the primary and secondary braking members are arranged opposite each other and applied to the same device, in this instance the rim of a friction-pulley.

Referring now to the drawings, showing the brake mechanism in elevation, 54 designates a bed-plate, to which is secured the bearing 38 for the driving-shaft 10 of a mo-

tor. To the power-transmitting shaft 10 is keyed or otherwise rigidly fastened a friction-pulley 11, having a broad rim 12, which is adapted to coact with the brake-shoes.

A double rocker-arm 13 is mounted loosely upon the shaft 10 and kept in place thereon by being connected to the magnet-frame 14 by means of the bolts 17 17' and lock-nuts 18 18', respectively. An antifriction-metal bushing 15 separates the shaft 10 from this rocker-arm and magnet-frame 14. Means for lubricating the shaft and bushing are indicated at 16.

The lower part of the magnet-frame 14 contains a solenoid 19, within which is a plunger or movable core 20, having a disk 23 rigidly attached to its lower end. Between the lower end of the magnet-frame 14 and this disk, so as to surround the lower end of the plunger 20, are placed the springs 21 and 22, one within the other. These springs which thus encircle the plunger press against the lower portion of the magnet-frame 14 and the disk 23 to force the plunger 20 in a downward direction.

Primary brake-levers 27 27' are pivoted at 28 28', respectively, to the extreme ends of the double rocker-arm 13. The primary brake-shoes 29 29' are pivoted upon the levers 27 27' at the intermediate points 30 30', respectively. Fastened to the lower end of the plunger 20 by means of the pin 24 are two toggle-links 25 and 25', which serve to transmit any motion of the plunger 20 to the primary brake-levers 27 27', these links being connected to the brake-levers at 26 26', respectively.

Leaf-springs 31 31' are interposed between a flattened portion 53 on the shoes 29 29' and the levers 27 27' adjacent the pivotal points 30 30', respectively. The effect of this construction is that the brake-shoes 29 29' are normally held out of contact with the friction-pulley 12.

Integral with the bearing standard or support 38 or suitably secured thereto are two projecting lugs 37 37', to which are pivoted, by means of the pins 36 and 36', the secondary brake-levers 32 and 32', respectively. These additional brake-levers have pivoted to them by means of the pins 34 34' the secondary brake-shoes 33 33'. The additional 105 brake-shoes 33 33' are also provided with

flattened portions 52, against which bears a flat spring 35, engaging at its ends the brake-levers 32 32'. The springs between the brake-levers and brake-shoes tend to overcome any tilting of the shoes when the same are released from the face of the pulley 11 as well as hold said shoes normally out of contact with the rim 12 of the pulley.

At the upper ends of the brake-levers 32 32' are shown two lugs 40 40', the latter being provided with enlarged holes through which passes the bolt 41. Between the lugs and on this bolt is mounted a compression-spring regulated by the nut 42. The spring tends to move the brake-levers 32 32' apart; but this movement is limited by the head of the bolt and by the nut 42.

The extreme ends of the brake-levers 32 32' are provided with pins 43 43', which enter and are adapted to slide in the slot 51 of a link-plate 44. This link-plate 44 is connected to the rocker-arm 13 by means of two turnbuckles comprising the couplings 49 49' and the link members 50 50' and 48 48'. In this instance the links 50 50' are pivoted at their upper ends to pins 45 45', which are secured to the lower portion of the link-plate 44. The links 48 48' are slotted at their lower ends to receive the pins 46 46', projecting from the rocker-arm 13. The couplings 49 49' are of course right and left hand screw-threaded and fit on corresponding screw-threaded ends of the aforementioned links.

35 The outward movement of the brake-levers 32 32' is adjustably limited by the bolt-head and nut, but are positively limited by the ends of the slot 51. The shoes 33 33' may be brought closer to the rim 12 of the pulley by turning the couplings 49 49'; but the main purpose of these couplings is to vary the application of the secondary shoes after the primary shoes have been applied. When the parts are properly adjusted, they 45 will appear as in the figure—that is, the spring 39 will be able to hold the shoes 33 33' in their releasing position and transmit a tension through the link-plates 44 and the turnbuckles so that the secondary shoes shall be 50 applied immediately after the primary shoes are applied.

It will be noticed that all parts are symmetrically arranged, so that the brake will operate equally as well whether the pulley is 55 rotating in one direction or the other. I preferably place the pins 46 46' nearer to the shaft 10 than to the pivotal points 28 28', so that the secondary shoes shall be applied a very short time after the primary shoes are 60 set, and, furthermore, so as to obtain a substantial diametral pull on the secondary brake-levers, the turnbuckles being for all practical purposes in such position as to apply nearly equal braking action on the shoes 65 33 33'.

The operation of my device is as follows: Let it be assumed that the magnet 14 is energized so that the plunger 20 is raised against the action of the springs 21 and 22 and exerts a pull on the toggle-links 25 25' to rock the 70 brake-levers 27 27' about the pins 28 28'. The brake-shoes 29 29' will then be held in their releasing position, as shown, and their outer surfaces will be maintained concentric by the springs 31 31' bearing on the flattened portions 53 of the shoes. The pulley is now free to revolve. Supposing the pulley to be revolving in a clockwise direction, let it be desired to apply the brakes. The first operation would be to interrupt the circuit through the solenoid 19, whereupon the 75 springs 21 and 22 would act through the toggle-joint at 24 to force the levers 27 27' outwardly, thus applying the primary brake-shoes 29 29' against the inner surface or periphery of the rim 12 of the pulley 11; the pins 28 28' serving as fulcrums for the levers 27 27'. Since the double rocker-arm 13 is mounted loosely on the shaft 10 and the magnet-frame 14 is rigid with said rocker-arm, the 80 latter will be turned in a clockwise direction and effect the application of the secondary brake-shoes on the outer surface or periphery of the pulley-rim 12. When the primary 85 brake is applied, the friction between the 90 shoes and the inner surface of the pulley-rim is sufficiently great to exert strong pulls on both the arms of the rocker-arm 13, but in opposite directions, the rocker-arm being 95 therefore rotated about the shaft 10. The 100 result of this action is that the pin 46 places the turnbuckle at the right in tension, which is transmitted to the link-plate 44 and thence through the pins 43 43' to both brake-levers 105 32 32'. The latter will be drawn together, the pins 36 36' being the fulcrum-points, and the secondary brake-shoes 33 33' will be applied to the outer surface or periphery of the 110 pulley-rim 12 with great force.

It will be seen that the primary and secondary brake-shoes are placed opposite each other. This is for the purpose of preventing undue strain on the pulley-rim, which might occur if the brake should be suddenly and very forcibly applied either to the outer surface alone or to the inner surface alone. I therefore not only secure greater braking action, due to a greater area of frictional engagement and an accumulation of power transmission, but also neutralize any diametral strains on the pulley-rim and limit the strain thereon to a circumferential tension.

When the rocker-arm is moved in a clockwise direction, the pin 46' moves loosely in the slot 47'. If the rocker-arm rotates in the opposite direction, the pin 46 would ride loosely in the slot 47. In either case the link-plate 44 would be placed in tension to move the brake-levers 32 32' toward each 120 125 130

other against the action of the spring 39, the pins 43 43' being allowed free play in the slot 51. In case the pulley rotated in a clockwise direction and the brakes were applied the pin 5 43' would remain in the end of its slot, but the link-plate 44 would obviously be moved a short distance to the right and downwardly, so that the pin 42 would take a position to the left of the end of the slot 51 after 10 the secondary shoes were applied.

When it is desired to release the pulley and the driving-shaft to which it is secured, the magnet is energized, whereupon the shoes 29 29' will be removed from contact with the 15 inner surface of the pulley-rim 12. The rocker-arm will now be free to rotate. Tension will be exerted by the spring 39 through the link-plate 44 and the right-hand turn-buckle in an opposite direction to that there- 20 in exerted before to rotate the rocker-arm back to its normal position. At the same time the secondary brake-shoes will be moved away from the outer surface of the pulley- rim, so that the shaft and pulley will then be 25 free to revolve. It will thus be seen that the spring 39 acts as a centering device to restore the brakes to normal position upon the energization of the magnet 14.

It is to be noted that I have shown two 30 springs 21 and 22 for setting the primary brakes; but only one spring may be used, if desired. It is preferable, however, to employ two springs, each of sufficient strength to apply the primary brakes and hold it ap- 35 plied, so that if one spring should break or become otherwise deranged the other could be relied upon for the proper operation of both brakes. Furthermore, the arrangement shown includes a double primary 40 brake and a double secondary brake, such that if one of the primary brakes becomes inoperative the other would be sufficient to effectively apply the secondary brakes. So, also, if one of the secondary brakes becomes 45 inoperative the other could still be applied. In other words, either primary brake is able by its impressed motion, due to its frictional contact with the pulley-rim, to actuate intermediate connections, and thus effect the ap- 50 plication of either one or both of the secondary brakes. The result, therefore, of the double arrangement of setting springs and brakes is not only an increase in braking power, but also a safeguard against emergencies so far as derangement of the braking 55 mechanism is concerned.

Having thus fully described my invention so that any one skilled in the art may make, use, and construct the invention and without limiting myself to any of the details of construction or arrangement of parts, what I claim, and desire to have protected by Letters Patent of the United States, is—

1. The combination with a moving mem- 65 ber, of a brake associated therewith, an addi-

tional brake for said moving member, and means for effecting the application of said additional brake after the setting of said first-named brake.

2. The combination with a moving mem- 70 ber, of a brake therefor, an additional brake opposite said first-named brake, and means coacting with said first-named brake for effecting the application of said additional brake after the first-named brake is applied. 75

3. The combination with a moving mem- 80 ber, of a brake therefor on one side of said member, an additional brake opposite said first-named brake and on the opposite side of said member, and means coacting with said first-named brake after the setting thereof for applying said additional brake.

4. The combination with a rotating mem- 85 ber, of a primary brake therefor, a secondary brake for said rotating member, and means for applying said secondary brake from said primary brake after the application of the latter.

5. The combination with a rotating mem- 90 ber, of an inner primary brake therefor, an outer secondary brake opposite said primary brake, and connections for effecting the application of the secondary brake after the setting of the primary brake.

6. The combination with a moving mem- 95 ber, of a double brake therefor, of an additional double brake adjacent said first-named brake, and connections for effecting the application of said additional double brake upon the application of said first- 100 named double brake.

7. The combination with a moving mem- 105 ber, of a primary double brake, a secondary double brake adjacent said primary double brake, and means coacting with the primary double brake for applying the secondary double brake.

8. The combination with a rotating mem- 110 ber, of an inner primary double brake, an outer secondary double brake, and connec- tions between said brakes.

9. The combination with a moving mem- 115 ber, of a brake associated therewith and movable in the direction of motion of said member, an additional brake in close proximity to said first-named brake, and means for effecting the application of said additional brake to said member when said first-named brake is applied.

10. The combination with a moving mem- 120 ber, of a brake associated therewith and movable in the direction of motion of said member, an additional brake in close proximity to said first-named brake, and means for effecting the application of said additional brake to said member upon the setting of said first- 125 named brake.

11. The combination with a moving mem- 130 ber, of a brake associated therewith and movable in the direction of motion thereof, an

- additional brake opposite said first-named brake, and means effecting the application of said additional brake when said first-named brake is applied.
12. The combination of a moving member and two devices arranged opposite each other and on opposite sides of said moving member for retarding the motion of said member, one of said devices being brought into operation by the other device through frictional engagement of the latter with said member.
13. The combination with a rotating member, of a device for retarding the motion thereof, an additional device for retarding the motion of said member, and means co-acting with the first-named device for bringing the said additional device into operation through the frictional engagement of said first-named device with said rotating member.
14. The combination with a moving member, of a brake associated therewith and movable in the direction of motion of said member, and a second brake adjacent said first-named brake and actuated by the impressed motion thereof due to its frictional contact with said moving member.
15. The combination with a moving member, of a brake associated with a portion of said moving member and movable in the direction of motion of said member, and a second brake associated with an opposite portion of said moving member and actuated by the impressed motion of said first-named brake due to its frictional engagement with said moving member.
16. The combination with a rotating member, of an inner primary brake movable in the direction of motion of said member, an outer secondary brake opposite said primary brake, and means for effecting the application of said additional brake when said first-named brake is applied.
17. The combination with a rotary member, of a brake for acting thereon, a support for said brake constructed to move around the axis of said member, and a second brake for said member and actuated by the impressed movement of said support due to frictional engagement of said first-named brake with said member.
18. The combination with a rotary shaft, of a friction-pulley on said shaft, a brake associated with said friction-pulley and movable in the direction of rotation thereof, an additional brake for said pulley, and means actuated by the impressed movement of said first-named brake due to frictional engagement of the first-named brake with the said friction-pulley for applying said additional brake to said pulley.
19. The combination with a rotary friction-pulley, of means for retarding the motion of said pulley and movable around the axis thereof, and additional means for retarding the motion of said pulley, said additional means being operated by the impressed rotary movement of said first-named means.
20. The combination with a rotary shaft, of a friction-pulley thereon, arms connected at one end by a joint, brakes on said arms bearing on the pulley, means for normally forcing the arms apart to move said brakes into contact with said pulley, a support for said arms, and electromagnetic means carried by said support for forcing together said arms and relieving the brake-pressure.
21. The combination with a rotary shaft, of a friction-pulley on said shaft, a frame loose on said shaft, a brake supported by said frame and bearing on said pulley, an additional brake, and connections between said frame and said additional brake for effecting the application of the latter when the frame is tilted by the frictional engagement of said first-named brake with said pulley.
22. The combination with a rotary shaft, of a friction-pulley on said shaft, arms connected by a joint at one end, brakes supported on said arms and bearing on said pulley, means for moving said arms to release or apply said brakes, a support for said arms constructed to permit the same to tilt in the direction of rotation of said pulley, an additional brake associated with said pulley, and means actuated by the tilting of said support and arms due to frictional engagement of said first-named brakes for effecting the application of the additional brake.
23. The combination with a rotary shaft, of a friction-pulley thereon, arms connected by a joint at one end, brakes supported by said arms and associated with said pulley, one or more springs for moving said arms to brake-applying position, an electromagnetic device for releasing said brakes, a support for said arms constructed to permit the same to tilt in the direction of rotation of said pulley, an additional brake for said pulley, and brake-applying means for said additional brake actuated by the tilting of said arms due to frictional engagement of said brakes.
24. The combination with a rotary shaft, of a friction-pulley secured thereto, a brake for application to the inner periphery of the pulley-rim, a support for said brake loose on said shaft, an additional brake for application to the outer periphery of the pulley-rim, and connections between said outer brake and said support for the inner brake, the outer brake being controlled by the displacement of said support in arc due to the frictional contact between the inner brake and the pulley-rim.
25. The combination with a rotary shaft, of a friction-pulley thereon, a brake associated with the inner periphery of the pulley-rim, a support for said brake loose on said shaft, an additional brake associated with the outer periphery of the pulley-rim, and means for

operating said additional brake controlled by the displacement of said support in arc due to the frictional contact of the first-named brake with the inner periphery of the pulley-
5 rim.

26. The combination with a rotary shaft, of a double rocker-arm loose thereon, a solenoid connected to said rocker-arm, a brake-pulley on said shaft, levers pivoted on said 10 rocker-arm and controlled by said solenoid, brakes acting on said pulley and controlled by said levers, additional brakes acting on said pulley, and means controlled by the displacement of said rocker-arm in arc for moving said brakes into operating position.

27. The combination with a rotary member, of a brake constructed to retard the motion thereof and movable around the axis of said rotary member, a second brake for acting 15 on said rotary member, means for applying said second brake by the actuation of said first-named brake, electromagnetic means for releasing said first-named brake, and means for restoring both of the brakes to normal.

28. The combination with a movable member, of a brake associated therewith, an additional brake for said movable member, means for effecting the application of said additional brake upon the setting of said first- 20 named brake, electromagnetic means for releasing the primary brake, and means for restoring both of said brakes to normal position upon the operation of said electromagnetic means.

29. The combination with a movable member, of a brake therefor, an additional brake for said member, means coacting with said first-named brake for applying said additional brake, means for releasing said first-named 25 brake, and means coacting with said brake-applying means of said additional brake for restoring both brakes to normal.

30. The combination with a movable member, of a device for retarding the motion thereof, an additional device for retarding the motion of said member, means coacting 30 with the first-named device for bringing said additional device into operation through the frictional engagement of said first-named device with said movable member, and means for restoring said brakes to normal position.

31. The combination with a rotating member, of a primary brake therefor, means for applying said brake, a secondary brake, means coacting with the primary-brake-applying 35 means for applying said secondary brake, and a spring for restoring said brakes to their normal positions.

32. The combination with a rotating shaft, of a friction-pulley thereon, a primary brake

to act on said pulley, a rocker-arm loose on said shaft, a brake-lever supported by said rocker-arm and supporting said brake, means for moving said lever to apply said primary brake, a secondary brake, an additional 65 brake-lever therefor, connections between said rocker-arm and additional brake-lever, electromagnetic means for releasing said primary brake, and a single restoring means for both of said brakes.

33. The combination with a rotating shaft, of a friction-pulley thereon, a double rocker-arm loose on said shaft, primary brake-levers supported by said rocker-arm, primary brake-shoes supported by said levers and associated 70 with the inner periphery of the pulley-rim, means for moving said primary brake-levers to apply said primary brake-shoes, secondary brake-levers, secondary brake-shoes supported thereby and associated with the outer periphery of the pulley-rim opposite said primary brake-shoes, adjustable connections between said rocker-arm and said secondary brake-levers, electromagnetic means for releasing the primary brake levers and shoes, 75 and a spring associated with the free ends of said secondary brake-levers for restoring the same to normal and for coacting with said adjustable connections to rotate said rocker-arm to normal position.

34. The combination with a moving member, of a brake therefor, electromagnetic means for releasing said brake, and a plurality of concentrically-arranged springs for applying said brakes.

35. The combination with a moving member, of means for retarding the motion thereof, a plurality of concentrically-arranged springs for operating said retarding means, and means for releasing said retarding means.

36. The combination with a moving member, of a brake therefor, a solenoid, a plunger for said solenoid, a plurality of independent springs surrounding one end of said plunger, and means for connecting said brake and 105 plunger.

37. The combination with a brake-pulley, of a primary brake and a secondary brake for said pulley, a solenoid, a plunger for said solenoid, a plurality of independent springs for moving said plunger, and connections between said plungers and said brakes.

In testimony whereof I have signed my name to this specification in the presence of two subscribing witnesses.

AUGUST SUNDI.
